UNITED STATES PATENT OFFICE.

FRED K. PHILLIPS, OF NEW YORK, N. Y., ASSIGNOR TO FELIX JELLENIK,
TRUSTEE, OF SAME PLACE.

DESIGN FOR A LAMP-BODY.

SPECIFICATION forming part of Design No. 28,482, dated April 19, 1898.

Application filed February 21, 1898. Serial No. 671,203. Term of patent 14 years.

To all whom it may concern:

Be it known that I, FRED K. PHILLIPS, a citizen of the United States, residing at New York city, State of New York, have invented 5 and produced a new and original Design for Lamp-Bodies, of which the following is a specification, reference being had to the accompanying drawings, forming part thereof.

Figure 1 is a side elevation of a lamp-body, 10 showing my new design. Fig. 2 is a top view of the same looking down.

As shown in the drawings, the leading or characteristic feature of my design consists 15 of a cylindrical base portion A, substantially spherical top portion B, cylindrical neck C of smaller diameter than either the base portion or the top portion and connecting the base

portion to the top portion, and a bell-shaped outwardly-flaring reflector D, the smaller end thereof connecting with the neck between the 20 top and bottom portions.

E represents the chimney or hood of the reflector and is of a cylindrical shape, resting on the top of the reflector.

Having described my invention, what I 25 claim as new, and desire to secure by Letters Patent, is—

The design for a lamp-body as herein shown and described.

FRED K. PHILLIPS.
